Application January 8, 1953, Serial No. 330,196

2 Claims. (Cl. 214—313)

This invention relates to handling devices and more particularly to a mobile, power operated lift adapted to engage a special container for moving it, including raising, lowering and dumping, and having specially designed power operated engaging means for the container.

In various industries, such as fruit growing, and the like, it is necessary to move relatively large containers of fluent material. This may include lifting the container from one position on the ground or other support and shifting it to another position at the same or a different level. It may also be necessary to dump the contents of the container at a given location. Because of the size and weight of the loaded containers, it is impractical to perform these tasks manually.

In the past, various machines for loading and unloading or moving heavy containers have been devised, but these have frequently suffered from lack of flexibility of movement, or have been incapable of dumping the contents without manual assistance.

Accordingly, it is an object of the present invention to provide a device adapted to engage the upper rim of a specially constructed container, lift the container and move it to a desired location, either on the same or a different level, and if desired to dump the contents thereof.

A further object of the invention is the provision of an articulated lift, adapted to engage a container and shift its position in both the horizontal and the vertical plane, including releasing the container in the same relative position or dumping it, if desired.

These and other objects of the invention will become apparent from the following description in conjunction with the accompanying drawings, in which

Fig. 1 is a side elevation of a device constructed in accordance with the present invention;

Fig. 2, a fragmentary side elevation to a reduced scale of the lower portion of the device of Fig. 1, and illustrating one method of mounting it on a tractor;

Fig. 3, a rear fragmentary elevation to an enlarged scale of the lower portion of the device of Fig. 1, with a portion of the base shown in section;

Fig. 4, a fragmentary front elevation of the device of Fig. 1, illustrating the same in raised position.

Fig. 5, a front elevation of the frame and bucket engaging member of Fig. 1;

Fig. 6, a top plan view of the device of Fig. 5, illustrating the manner of engaging a container;

Fig. 7, a schematic diagram of the hydraulic actuating system; and

Figs. 8, 9 and 10, a cross section through a valve actuating member illustrating it in the three possible positions of use.

Briefly stated, the loader includes a base adapted to be mounted on a tractor, or the like, and carrying an upright post or mast; means are provided for rotating the post or mast through a complete circle. At the upper extremity of the mast, a boom is pivotally mounted and at the latter's other extremity a second or jib boom

2

is pivotally mounted. At the end of the jib boom a frame is mounted which has one angularly disposed arm fixed thereto and a second arm movably connected thereto which is adapted to engage the opposite side of a container from that of the fixed arm. Hydraulic pistons are mounted between the mast and the boom, the boom and the jib boom, and the jib boom and the movable arm, in order to produce relative movement or articulation between the pivotal members. A fourth is mounted between the jib boom and the frame, the latter of which is pivotally supported on the jib boom, in order to lift the frame for dumping the container. Means for supplying hydraulic fluid under pressure to the pistons and control by valves accessible to the operator of the tractor is also included.

Referring to the drawings, the loader comprises a base 10, having side members 11 and 12, joined by a top or web portion 13. The base may be mounted on channel members 14 and 15, carried by a tractor 16.

Supported between the members 11 and 12 is a bracket 17 which carries an upright sleeve 18. A post or mast 19 is received in the sleeve and has a collar 20 mounted just above the sleeve which engages a bearing 21 at the upper end of the sleeve. At the lower extremity of the mast is a gear 22. A mating gear 23 is mounted on a shaft 24 carried by bracket 17. At the lower end of shaft 24 a pinion 25 is mounted for engagement with a rack 26 which is attached to a rod 27, mounted for reciprocation in a cylinder 23.

At the upper end of the post 19 a pair of spaced trunnions 29 are mounted which pivotally mount a second post or boom 30 having a transverse shaft 31 carried by the trunnions 29.

In order to vary and maintain the posts 19 and 30 in the desired angular relationship, a cylinder 32 is provided, having a cap 33 at its lower end. The cap has a pair of spaced ears 34 for receiving a projection 35 extending from the collar 20, a pin 36 pivotally connecting the ears to the projection 35.

Extending through a cap 37 at the other end of the cylinder is a rod 38 having a piston 39 attached thereto and reciprocating within the cylinder. The other end of the rod is attached to a projection 40 at the side of the post 30 and spaced substantially intermediate its ends. Hydraulic lines 41, 41' extend into the cylinder 32.

The post 30 has a pair of trunnions 42 at its remote end which mount a transverse shaft 43, carrying a third post or jib boom 44. In order to adjust and maintain the angular relationship between the posts 30 and 44 a cylinder 45, which may be integral with or connected to the post 30, is mounted within the post. The cylinder is of conventional construction and carries a conventional double acting piston 46 to which is attached a projection 47 extending laterally outside the post 30 through a slot (not shown) therein. A push rod 48 is pivotally connected to the projection 47 at one end and to a projection 49 at the other, the latter projection being attached to a flange or shield 50 extending rearwardly from the sides of the post 44.

Suitable lines 51, 52 are connected to the cylinder 45 for the transmission of fluid between it and the hydraulic mechanism.

Referring more particularly to Figs. 1, 5 and 6 the post 44 has the central or web portion of a yoke 53 rigidly attached to it, the arms of the yoke 54 and 54' providing substantially an extension of the post 44. At the ends of the arms a frame 56 is pivotally carried by projections 57 and 58, pins extending through the arms and the projections.

The frame 56 has an upper rectangular portion having relatively short side members 60 and 61, on which the projections 57 and 58 are mounted, and relatively long

side members 62 and 63 rigidly connected thereto. Disposed at an angle to the rectangular portion are a pair of legs 64 and 65 which have an arcuate connector 66 at their lower end having a hook-shaped cross section and adapted to engage an internal flange 67 at the upper edge of a bucket 68.

Extending downwardly from the rectangular frame at the opposite side from the legs 64 and 65 are another pair of legs 69 and 70. Cross members 71 and 72, spaced from the side members 60, 61 of the frame, connect the legs 63 and 69, and 64 and 70, respectively.

A movable bucket engaging member 74 has a central arcuate portion 75 similar to the portion 66 of the fixed member and is attached at its side arms 76 and 77 to the lower end of a yoke having side member 78, 79. The central portion of the yoke is mounted on a rod 80 connected to a piston reciprocated in a cylinder 81 which is mounted on a rectangular portion of the frame. Hydraulic lines 82, 83 are connected to the cylinder and extend to a source of fluid.

In order to vary and maintain the desired angular relationship between the frame 56 carrying the bucket 68 and the post 44, a piston rod 84 has an end pivotally attached to an ear 85 of a bar 86 mounted on the rectangular portion of the frame. The rod is attached to a piston 87 reciprocated in a cylinder 88 which is mounted on the post 44 adjacent to the shaft 43. Suitable lines 89, 90 are attached to the cylinder.

In order to control the flow of fluid to the hydraulic lines, a lever 91 is pivotally mounted on a board 92 for each pair of the lines. Referring more particularly to Figs. 7 through 10, a pump 92 is illustrated which feeds into a reservoir 93 and out through a discharge line 94. The line 94 is connected to a manifold (not shown) which feeds to an intake 95 for each of the valves. The return conduit 96 of each of the valves is connected to a second manifold (not shown) which is attached to a suction line 97 feeding to a reservoir 98. From the reservoir the fluid is drawn into the pump for recirculation.

In Fig. 8 the valve member is shown in the position for permitting fluid under pressure to pass through the channel 99 in the valve and out the discharge line 100. At the same time fluid from the other side of the piston is returned through the conduit 101 of the valve through the channel 102 and out the discharge 96. In Fig. 9 the movable valve member 103 is shown in the position at which the passages of the valve are blocked, the pistons being prevented from movement within their respective cylinders under such circumstances.

In Fig. 10 the valve member 103 has been shifted to the right from the position of Figs. 8 and 9 so that channels 99 and 102 are blocked, but opening channels 104 and 105. With the valve in this position it will be understood that the flow through the conduits 100 and 101 is opposite to that of Fig. 8.

In the operation of the device the tractor is first moved to a position in proximity to the container 68 which is to be moved. The mast 19 is then rotated so that the posts 30 and 44 extend in a direction toward the container. By manipulation of the controls for the pistons 38 and 48 the height of the post 44 and the position of the frame carrying the container engaging members may be adjusted. As the container engaging members are lowered into position, the member 66 is engaged with the flange 67 of the container from which the movable member 74 is moved into opposing engagement by the operation of the piston 80. After the bucket is engaged, it may be lifted and moved to a different position without movement of the tractor, or it may be carried by the device as the tractor itself is moved for movement to a different location.

It will be understood that because of the arrangement of the post and frame and their articulation that within the range of movement the container may be shifted

laterally or vertically to any desired position. Furthermore, by the actuation of the piston rod 84 to pivot the frame about the pivot means 57 and 58, the frame and the container carried thereby may be tilted to dumping position.

Accordingly, it will be understood that the invention includes a container and engaging means adapted to be mounted on a tractor or the like and having a plurality of pivotally mounted arms, the lower or supporting post of which may be rotated to any desired position, the container and engaging means being mounted on a frame which can be pivotally moved to turn the container about a horizontal axis in order that it may be dumped.

While the embodiment of the invention which has been illustrated and claimed discloses mechanical means for engaging the container or bucket 68, such means including the internal bucket flange 67 and the fixed and movable engaging members 66 and 75, respectively, it will be understood that other clamping or securing mechanism may be employed advantageously. Another form of such mechanism desirably might be hydraulic in nature, including an appropriate cylinder and control whereby the bucket 68 could be engaged exteriorly thereof and thus clamped or securely locked into proper position with respect to the handling mechanism with which we are presently concerned.

Although one specific embodiment of the invention is shown and described, it will be understood that it is not limited to the specific construction disclosed, but that various modifications are within the scope thereof. Therefore, the invention is only limited as defined in the following claims.

What is claimed is:

1. A device for handling open top containers having an turned flange structure at their tops comprising a base for mounting on a movable support, a first post mounted on the base and extending upwardly therefrom, means for rotating the post relative to the base, a second post pivotally mounted on the first post, piston and cylinder means extending from the first to the second post, means for actuating the piston and cylinder means for adjusting the angular relationship between the posts, a third post pivotally attached to the outer end of the second post, piston and cylinder means mounted on the second post, means connecting the said piston means to the third post, means for actuating the said piston and cylinder means mounted on the second post, whereby the angular relationship between the second and third post may be adjusted, a frame pivotally mounted on the end of the third post remote from the second post, a first fixed container engaging member extending from the frame for engagement with the container flange at one side of the container, a second container engaging member pivotally connected to the frame and diverging from said first engaging member for engagement with the container flange at the opposite side of the container, piston and cylinder means mounted on the frame and connected to the second engaging means for actuation thereof, means for actuating said piston and cylinder means, a fourth piston and cylinder means mounted on the third post, the piston means being attached to the frame, and means for actuating the fourth piston and cylinder means.

2. Apparatus for handling material in which the material is disposed in open top containers having inwardly extending ledge portions adjacent their upper ends within the outline of the containers so that the containers may be positioned in side-by-side abutting relation, a frame having means for engaging a ledge portion of a container, means movably mounted on said frame for engaging an opposite ledge portion of the container and movable into and out of operative position on said opposite ledge portion, means to support said frame for vertical and lateral movement, power means for causing vertical and lateral movement of said support means, additional power means to move said movably mounted means on said frame into

and out of engagement with the opposite ledge portion of the container, other additional power means reacting between said support means and said frame for tilting said frame and the ledge engaging means thereon to move the container from an upright position retaining fluent material to a tipped position whereby the fluent material will fall by gravity from said container, and control means for actuating said power means to perform all of the functions without manual handling of the container.
